DESIGN FOR A CLOCK CASING

Max Schlenker, La Salle, and Joseph A. Reinhardt, Peru, Ill., assignors to General Time Instruments Corporation, New York, N. Y., a corporation of Delaware

Application October 17, 1936, Serial No. 65,344

Term of patent 7 years

To all whom it may concern:

Be it known that we, Max Schlenker and Joseph A. Reinhardt, citizens of the United States, residing in the city of La Salle and city of Peru, respectively, both in the county of La Salle and State of Illinois, have invented a new, original, and ornamental Design for a Clock Casing, of which the following is a specification, reference being had to the accompanying drawing, forming a part thereof.

The drawing is a perspective view of a clock casing showing our new design.

We claim:

The ornamental design for a clock casing, as shown.

J. A. REINHARDT.
MAX SCHLENKER.
